UNITED STATES PATENT OFFICE.

WILLIAM THOMAS BUCKINGHAM ROBERTS, OF LEICESTER, ENGLAND, ASSIGNOR, BY
MESNE ASSIGNMENTS, TO UNITED SHOE MACHINERY CORPORATION, OF PATERSON
NEW JERSEY, A CORPORATION OF NEW JERSEY.

SEAM-RUBBING MACHINE.

1,259,134.

Specification of Letters Patent. Patented Mar. 12, 1918.

Application filed June 26, 1916. Serial No. 105,897.

To all whom it may concern:

Be it known that I, WILLIAM T. B. ROBERTS, a subject of the King of England, residing at Leicester, Leicestershire, England, have invented certain Improvements in Seam-Rubbing Machines, of which the following description, in connection with the accompanying drawings, is a specification, like reference characters on the drawings indicating like parts in the several figures.

This invention relates to machines for rubbing or pounding seams and is herein illustrated in connection with a machine designed to operate upon the seams in parts of the uppers of boots and shoes.

One feature of the invention comprises a support for a seam including a ridge and a substantially flat portion into which the ridge merges, means coöperating with the ridge for feeding the seam, and means coöperating with the flat portion for rubbing or pounding the seam. In the illustrative machine the sides of the ridge flare outwardly so that as the seam is advanced the shoe part in which the seam is located is gradually opened until a considerable extent on each side of the seam lies flat on the flat portion of the support when the rubbing or pounding tool engages the seam.

This and other features of the invention including certain details of construction and combinations of parts will be described in connection with an illustrative machine and pointed out in the appended claims.

Referring now to the accompanying drawings,

Figure 1 is a perspective view of the block or support over which the work passes in the seam-rubbing operation;

Fig. 2 is a detail front elevation of the work-feeding and guiding and the seam-rubbing elements;

Fig. 3 is a side elevation of Fig. 2, and Fig. 4 is a plan view thereof;

Fig. 5 is a front part sectional elevation of the complete machine; and

Fig. 6 is a side part sectional elevation of the machine viewed from the left hand side of Fig. 5.

In this embodiment which is more particularly intended for seam rubbing upon light work three rolls 1, 2 and 3 are pro-

vided which coöperate with a fixed block or support 4.

The fixed block 4 is detachably supported upon a standard 5 and has a somewhat convex contour in the direction of travel of the work, the rubbing or pounding roll 2 being located above the highest portion at the center, the feed roll above the portion which drops away toward the front of the machine, and the pressing or ironing roll 3 located above the portion which drops away toward the rear of the machine. The upper surface of the block from beneath the center of the rubbing or pounding roll to its rearward extremity has a surface 6 which is substantially flat, considered transversely to the line of travel of the work through the machine, and consequently the work in the neighborhood of the seam is, in passing beneath the rubbing or pounding and pressing or ironing rolls, laid flat down upon this portion of the support and receives the desired degree of treatment even if it should have deviated somewhat from its intended direction of travel beneath these rolls.

For some distance from the front of the block toward the highest point of the top of the block each side is beveled off to form two faces 7, 8 inclined to each other at an angle of about 60° and meeting to form a ridge 9 which is convex, considered from front to back of the block, in accordance with the general convex contour of the block in that direction. Toward the highest point of the block the inclination of the sides changes gradually and the beveled off faces no longer meet at the ridge but leave a flat portion 10 which gradually widens to practically the full width of the block at the highest point thereof. This form of the block permits the work to be guided with great ease and accuracy toward and under the rubbing or pounding tool. The two portions of the work which are joined by the seam are pulled one over each side of the ridge, the rough part to be rubbed down projecting freely upwardly, and the seam can with ease be located upon and guided along the ridge toward the rubbing or pounding tool 2, the gradually widening flat 10 in the immediate vicinity of the tool gradually spreading the work to

come flat to the tool without displacing it from the desired line of feed or unduly distorting the material. The movement of the work over the faces of the stationary block 5 moreover has a decided smoothing effect upon the work. To prevent undue distortion of the work and make the change from the sharp-edged ridge portion 9 to the flat work table 6 still more gradual it is also convenient 10 somewhat to concave or cut away in a direction from front to rear and transversely the portion 10 of the top of the block between the termination of the sharp ridge and the portion immediately beneath the 15 tool as is indicated in Fig. 3.

The feed roll which is located almost in contact with the rubbing or pounding roll is conveniently formed of two parts; one of 20 these is a cylindrical member 1 coned at the end 11 and is bored out longitudinally to receive the other which is formed of a spindle 12 passing through the bore and bearing at its end which projects out of the bore at the coned end of the first member a 25 short cylindrical member 13 also having a coned end 14 the apex of which is directed toward the apex of the cone 11 on the other member. The coned faces are preferably smooth, and the feeding taking place entirely by friction. 30

The angles of the cones are such that a parallel-sided inverted V passage is formed for the work to pass through between these coned portions and the inclined faces 7, 8 35 on the forepart of the block. The cone 11 on the first cylindrical member 1 is truncated so as to leave a narrow face around the opening of the bore through which the spindle passes, and a similar face is formed 40 by truncation of the other cone 14 so that a perpendicularly-sided groove is formed around the feed roll between the coned portions and constitutes a passage through which the upstanding portions of the work 45 which are to be rubbed down can pass as the work travels between the feed roll and the ridge 9 on the block 4. The two cylindrical portions 1, 13 of the feed roll are connected to be rotated together but means are 50 provided which allow of adjustment of the spindle 12 longitudinally in the bore to vary as desired the space between the faces on the ends of the conical portions. This adjustment is secured by means of a spindle 46 55 which is fixed against movement longitudinally of the member 1 and at one end is threaded into the spindle 12 and at the other end carries a milled nut 47, the spindle 12 being held against rotation relatively to the member 1 by engagement of a pin 48 on the latter with a slot in the former. Moreover the member 1 and the pinion fixed to it are mounted in bearings which permit a certain amount of lateral play so that the feed 60 65 vice can center itself upon the work which

is passing along the ridge on the block. The feed device is urged yieldingly toward the work by a spring 16 pressing upon the upper surface of a member 17, which has bearings 18, 19 for the member 1, and is pivoted 70 at 20 on a carrier member 21 and provided with a slot 22 in which a limit stop 23 on the member 21 engages.

The rubbing or pounding tool 2 is formed of the castellated or grooved end of a driven 75 shaft 24 which is also mounted so that it is pressed upon the work by adjustable spring pressure. To this end a spring 25 is provided which presses upon a bracket 26, having bearings 27, 28 for the shaft 24, the 80 bracket being provided with trunnions, one of which is shown at 29, mounted in bearings in the frame. It is important to round off the edges of the projections between the grooves on the tool so as to avoid damaging 85 the work. To raise the tool from the work when for any reason a part only of a work piece is to be operated upon a rod 30 bears at its upper end on a lug 31 of the bracket 26 and is adjustably threaded at its other 90 end into a pivotal member in one arm of a lever 32. The lever 32 is mounted on a pivot 33 on the frame and at one end has a downwardly turned portion 34 acting as a limit stop. The lever 32 may be connected 95 as convenient to treadle or other operating mechanism.

A smooth surfaced pressing or ironing roll 3 of small diameter is located close to and behind the roll 2 and is also mounted 100 to be urged on to the work by adjustable spring pressure in the same way as the feeding roll. It has formed upon it one or more flat faces 35 which act to permit the forward end of a piece of work as it emerges from 105 beneath the roll 2 to pass without hindrance beneath the ironing member as the latter rotates.

If desired the portion of the spindle of the feed roll between the coned portions 110 may be castellated or grooved as shown to render that part operative in feeding the work by engaging the upstanding portion of the work as the latter passes along the ridge.

To facilitate the adjustment of the spring pressure upon the feed roll and the rubbing or pounding roll there are provided, in connection with the springs 16, 25 adjusting handles 36, 37 which are pivoted in supports on the frame and carry notched cams (one of which is shown at 38) adapted to lock in different depressed positions the plungers 39, 40 which co-act at their lower ends with the springs 16, 25 and at their upper ends are beveled to engage the notches. A similar arrangement may, if desired, be provided for the pressing or ironing roll although in the machine shown the adjustment of the spring pressure on this 120 125 130

member is effected by an adjustable screw stud 41.

Under some circumstances the distance of the feeding roll or the ironing roll from the block or from each other may need to be varied and to this end the carrier members 21 and 42 of the feeding roll and ironing roll respectively are mounted to swing on the counter shaft 43 which carries the pinion from which the pinions fast to the feeding roll and ironing roll are driven. The carrier members are adjusted and set in adjusted position by a screw 44 threaded in the carrier 21 and bearing on the carrier 42 and by two screws threaded in the frame and bearing respectively on the tops of the carrier one of these screws being shown at 45.

Having thus described my invention, what I claim and desire to secure by Letters Patent of the United States is:—

1. A machine of the class described having, in combination, a support for a seam comprising a ridge and a substantially flat portion into which the ridge widens, means coöperating with the ridge for feeding the seam, and means coöperating with the flat portion for rubbing or pounding the seam.

2. A machine of the class described, having, in combination, a support for a seam comprising a ridge and a substantially flat portion into which the ridge widens, means coöperating with the ridge for feeding the seam, means coöperating with the flat portion for rubbing or pounding the seam, and other means also coöperating with the flat portion for pressing or ironing the seam.

3. A machine of the class described having, in combination, a support for a seam comprising a ridge along which the seam is guided and a substantially flat portion into which the ridge widens, a roll coöperating with the ridge for feeding the seam, and a fluted roll coöperating with the flat portion for rubbing or pounding the seam.

4. A machine of the class described having, in combination, a support for a seam comprising a ridge along which the seam is guided and a substantially flat portion into which the ridge widens, a roll coöperating with the ridge for feeding the seam, a fluted roll coöperating with the flat portion for rubbing or pounding the seam, and a roll having a flat area for pressing or ironing the seam.

5. A machine of the class described having, in combination a support for a seam comprising a ridge and a substantially flat portion into which the ridge widens, a feed roll having a cut-away portion provided with flaring sides adapted to embrace the ridge, and a pounding or rubbing roll arranged to coöperate with the flat portion.

6. A machine of the class described having, in combination a support for a seam

comprising a ridge and a substantially flat portion into which the ridge widens, a feed roll having a cut-away portion provided with flaring sides adapted to embrace the ridge, a pounding or rubbing roll arranged 70 to coöperate with the flat portion, and a pressing or ironing roll also coöperating with said flat portion.

7. A machine of the class described having, in combination, a support for a seam 75 comprising a ridge and a substantially flat portion into which the ridge widens, a feed roll comprising two conical portions adapted to extend one on each side of said ridge, means whereby the distance between said 80 portions may be varied, and means coöperating with the flat portion for rubbing or pounding the seam.

8. A machine of the class described having, in combination a support for a seam 85 comprising a ridge and a substantially flat portion into which the ridge widens, a feed roll comprising two conical portions adapted to extend one on each side of said ridge, means whereby the distance between said 90 portions may be varied, means coöperating with the flat portion for rubbing or pounding the seam, and a roll also coöperating with the flat portion for pressing or ironing the seam.

9. A machine of the class described having, in combination a support for a seam comprising a ridge and a substantially flat portion into which said ridge widens, a feed roll coöperating with the ridge, a rubbing 100 roll and an ironing roll both coöperating with the flat portion, and means for rotating said rolls in a direction to advance the seam from the feed roll to the rubbing roll and then to the ironing roll.

10. A machine of the class described having, in combination a support for a seam comprising a ridge and a substantially flat portion into which the ridge widens, a feed member, a pounding member and an ironing member arranged to act successively upon the work, and means for operating said members.

11. A machine of the class described having, in combination a support for a seam, 115 a feed roll, a rubbing roll and an ironing roll arranged to coöperate therewith, and means whereby the distance between said rolls may be varied.

12. A machine of the class described having, in combination a support for a seam, 120 a feed roll, a rubbing roll and an ironing roll arranged to coöperate therewith, and means for moving the rubbing roll away from the support during the operation of 125 the machine.

13. A machine of the class described having, in combination a support for the seam comprising a ridge formed by oppositely inclined faces and a substantially flat por- 130

tion into which the ridge widens, and mechanism for feeding a seam along said ridge and for rubbing it upon the flat portion.

14. A work support for a seam pounding machine comprising a ridge formed by oppositely inclined faces, and a substantially flat portion into which the ridge widens, the outline of the ridge and substantially flat portion being slightly convex with a cavity located near its highest portion.

15. A machine of the class described, having, in combination, a support for a seam comprising a ridge and a substantially flat portion into which the ridge widens, and means coöoperating with the flat portion for operating upon the seam.

16. A machine of the class described, having, in combination, a support for a seam comprising a ridge and a substantially flat portion into which the ridge widens, a feed roll having a cut-away portion provided

with flaring sides adapted to embrace the ridge, and means coöoperating with the flat portion for operating upon the seam.

17. A machine of the class described, having, in combination, a support for a seam comprising a ridge and a substantially flat portion into which the ridge widens, a feed roll having a cut-away portion provided with flaring sides adapted to embrace the ridge, means for varying the width of the cut-away portion, and means coöoperating with the flat portion for operating upon the seam.

18. A work support for a machine for operating upon seams comprising a ridge formed by oppositely inclined faces and a substantially flat portion into which the ridge widens.

In testimony whereof I have signed my name to this specification.

WILLIAM THOMAS BUCKINGHAM ROBERTS.
